(57) **CLAIM**

The ornamental design of trash can with internal storage cavity, as shown and described.

DESCRIPTION

The article is a trash can intended for indoor and/or outdoor use. The storage cavity provides a clean place for the storage of items such as spare garbage bags.

FIG. 1 is a top view of a trash can with internal storage cavity showing my new design;

FIG. 2 is a perspective view thereof; and,

FIG. 3 is a cross sectional view taken along the line 3—3 of FIG. 2.

1 Claim, 2 Drawing Sheets

FIG. 1

FIG. 2**FIG. 3**
